UNITED STATES PATENT OFFICE.

CLARENCE J. ALEXANDER, OF SEATTLE, WASHINGTON.

FISH-CARRYING SCOW.

1,262,426.

Specification of Letters Patent.

Patented Apr. 9, 1918.

Application filed February 26, 1917. Serial No. 150,956.

To all whom it may concern:

Be it known that I, CLARENCE J. ALEXANDER, a citizen of the United States, residing at Seattle, in the county of King and State of Washington, have invented certain new and useful Improvements in Fish-Carrying Scows, of which the following is a specification.

This invention relates, more especially, to fish-carrying scows or barges, and its object is the improvement of vessels of this class and also the provision of efficient means whereby the vessels may be quickly and economically unloaded.

With these ends in view, the invention consists in the novel construction and adaptation of devices, as will be hereinafter described and claimed.

In the accompanying drawings, Figure 1 is a plan view of a vessel embodying my invention. Fig. 2 is a transverse vertical section through 2—2 of Fig. 1 and illustrating a portion of a conveyer supported by a float. Fig. 3 is a fragmentary perspective view of a barge such as shown in the preceding views.

Referring to the drawings, the numeral 5 designates the hull of a barge or similar vessel having a deck 6 and provided with guards 7 and 7¹ at opposite sides.

Provided upon and rigidly secured to the deck 6 are longitudinal and transverse walls 8, 8¹ and 9, 9¹ affording an inclosure which is divided by longitudinal partition members 10, 10¹ 10² and transverse partitions 11, 11¹ and 12, 12¹ to furnish compartments A, B, C, C¹, D and D¹.

The various walls and partitions are formed of planks—those of the walls being rigidly secured to supporting posts, such as 13, while the outer and inner ends, respectively, of the partition planks removably extend into grooves or housings provided between upright cleats 14 and 15 secured to said walls and posts 16.

Communicating with compartment A, I provide an opening or port 17 extending from the deck 6 to the upper plank 8², Fig. 3, in the wall 8. At opposite sides 50 of said opening are reinforcing posts 18, to which are secured cleats 19 serving with the adjacent planking ends, as 20, to provide grooves to accommodate the ends of removable planks such as 21 which are employed to close, more or less, the wall opening 17.

To conduct the fish from said opening I employ a chute 22 whose lower end may be supported upon the side of a conveyer 23, Fig. 2, and whose upper end is supported upon a selected one of a number of rods 24 secured to the posts 18 or to a rod 24¹ provided in a recess 25 of the guard 7.

26 represent hooks provided on the underside of the chute for engagement with one of the rods 24 or 24¹. 27 represents extension or wing pieces which may be utilized when necessary, to close any outlet for escape of fish between the opening 17 and the adjacent end of the chute when the latter is taking fish from the deck level.

The above-mentioned conveyer may be of any suitable type and has its receiving end desirably supported to a float 28 having up and down tidal movements with the barge 5.

The operation of the invention may be explained as follows:

The barge at the fishing place is loaded by distributing the fish among the various compartments A, B, C, etc., so as to regulate the trim of the vessel, whereby it can be towed to the factory or shipping point, without danger of losing the cargo.

Upon arrival at destination, the chute 22 is attached by hooks 26 to the uppermost 85 of the rods 24 and the upper of the port closing boards 21 is removed, whereupon the fish in the compartment A above the level of the bottom of the then effective opening, will escape therethrough to be discharged by the chute.

After the depth of the fish has been thus lowered in compartment A, the upper board or two of partition 10 is removed, resulting in the upper portion of the fish in compartment B being caused to flow by gravity through the compartment A and the chute. Then, in like manner, the upper boards of partitions 11 and 12 are removed to allow the upper courses, so to speak, of 100 fish in compartments C and C¹ to successively flow in the directions indicated by arrows X through compartments B and A to be discharged by the chute. Ordinarily the fish will be wet or slimy enough to 105 enable them to flow freely, but such flow may be facilitated by sprinkling the fish with water from a hose.

When the upper portions of the load within compartment A at one side of the boat, 110 and all compartments B, C and C¹ on the other side have been discharged, the remain-

ing fish in these compartments are similarly discharged, stratum by stratum.

By first discharging the fish from compartments A, B, C and C¹, the weight of the fish remaining in compartments D and D¹ is utilized to cause the barge to "heel" or incline toward the delivery side, thereby promoting a rapid discharge, and finally the partitions 11¹ and 12¹ are removed for the 10 delivery of the fish, as indicated by arrows y, from compartments D and D¹ through compartment A and the chute.

While I have described the invention as applied to a scow or barge, it is to be understood that I do not limit myself to vessels which are to be towed, as where the fish are to be transported for long distances my devices may be advantageously used on power-propelled vessels.

20 What I claim, is—

1. A vessel having a space upon its deck inclosed by a frame comprising longitudinal and transverse walls, longitudinal and transverse removable partitions dividing the 25 aforesaid space into a number of compartments, a discharge opening provided in one of said walls and communicating with one of said compartments, a chute, and means for engaging the chute in a plurality of operative positions for the reception of contents from said opening.

2. In a vessel, the combination with an inclosure upon the deck of the vessel, and an outlet therefor at one side of the vessel, of means for directing the vessel's load from 35 various parts of the inclosure to cause the same to flow to said outlet; first, from in proximity to the latter, then from the side of the vessel remote therefrom and finally,

the remaining portion of the load on the side of the vessel in which said outlet is located.

3. In a vessel, the combination with the vessel's hull having a deck space inclosed by a wall, and removable partitions dividing said space into a number of compartments, said wall having an opening communicating with one of said compartments, a separable closure for said opening, and a chute for the delivery of fish discharged 50 from said opening.

4. The combination in a vessel having walls arranged to afford a rectangular deck space, one of said walls being provided with a discharge opening, of longitudinal and transverse partitions dividing said space into compartments, said partitions comprising a plurality of superposed members adapted to be successively removed, whereby selected of the compartments may be brought 60 into communication with each other with respect to successively lower elevations, said partitions affording means whereby the contents of all of said compartments may be discharged by gravity and guided to flow 65 to said discharge opening through one of the compartments.

5. A fish scow having superposed bins, a discharge chute at one side, and means whereby the discharge of the fish may be 70 controlled to list the scow toward the side containing the discharge chute.

Signed at Seattle, Washington, this 20th day of February 1917.

CLARENCE J. ALEXANDER.
